GARMENT HANGER

Michael Glaser, New York, N. Y.

Application November 25, 1942, Serial No. 466,905

1 Claim. (Cl. 223—87)

The present invention relates to a garment hanger of a type made of sheet material, such as laminated paper or cloth, or plastic material.

An object of this invention is to provide an improved garment hanger having a reinforced hook member made of the same relatively inexpensive sheet material as the main part of the hanger. This reinforced hook member can be subjected to great mechanical stress which heretofore could only be sustained by hooks made of relatively expensive material, such as laminated wood or metal.

Another object of this invention is to provide a garment hanger which may be stamped out in the form of a blank from a single sheet of inexpensive material, portions of said blank being folded one upon the other, one or more times, in order to obtain strength at those points of the hanger frame and/or the hook which are under the highest stress during the use of the hanger.

A further object of the invention is to provide an improved garment hanger made of sheet material with reinforced portions which hanger can be manufactured very economically by stamping same out from a sheet to form an integral blank, the latter being substantially completely utilized in an ingenious manner.

Still another object of this invention is to provide a rigid garment hanger composed entirely of inexpensive non-metallic sheet material which is attractive in appearance and can be made in any shape to conform readily to the outline of garments of various shapes. In the construction of this new hanger, materials such as metal, now essential for the war effort, are completely avoided and less strategic materials are utilized and the hanger frame is ingeniously constructed in such a manner that those portions of said frame and/or hook portions of the hanger which are subjected to the greatest stress are sufficiently strengthened by superimposing of layers of sheet material. The new hanger is not merely an inexpensive substitute to be used instead of the conventional wire hangers during this emergency, but has technical advantages over said wire hangers, thus it will maintain its place on the market in such times, when wire will again be abundantly available. Some of the advantages of my new improved hanger construction involve a larger supporting surface for the garments, thus keeping them in better shape at the places of contact and the prevention of contamination by rust which may occur, when wire hangers are used. Furthermore, the surface of the new garment hanger can be used for display

or advertising matter without detracting from the utility of the construction as a hanger.

Other objects and the nature and advantages of this invention will be apparent from the following description taken in conjunction with the accompanying drawings, wherein:

Figure 1 illustrates a plan view of one form of the new garment hanger;

Fig. 2 is a plan view of the development of the blank of sheet material from which the hanger in Fig. 1 is obtained by folding;

Fig. 3 is an enlarged cross section of the frame of the hanger shown in Fig. 1 taken along the line 3—3 and looking in the direction of the arrows;

Fig. 4 is an enlarged cross section of the hook of the hanger in Fig. 1 taken along the line 4—4 and looking in the direction of the arrows;

Fig. 5 illustrates a modified development of a blank of sheet material from which another modification of the new hanger can be obtained by folding;

Fig. 6 shows fragmentary plan view of a modification of the upper portion of the frame with the hook of the new hanger, obtained by folding the blank of Fig. 5 in one direction;

Fig. 7 shows a fragmentary plan view of a modification of the upper portion of the frame with the hook of the new hanger formed by folding the blank of Fig. 5 in the opposite direction from that shown in Fig. 6;

Fig. 8 is an enlarged cross section of the frame of the hanger of Fig. 6 taken along the line 8—8 and looking in the direction of the arrows;

Fig. 9 illustrates a fragmentary plan view of another modification of the new hanger, part of which is in folded plan position and part of which is in unfolded blank form.

Referring now to the drawings in detail, the hanger in Fig. 1 has the conventional general form of an isosceles triangle. The two upwardly converging sides 11 and 12 of the frame of said hanger form, advantageously, curved strips which conform generally to the outline of the garment, such as coat, overcoat, jacket or the like, to be supported by them. These sloping sides 11 and 12 and also a hook 13 at the meeting point of said sides involve reinforcing structure which will be described in detail below. A

straight strip 14 connects the lower ends of the diverging sides 11 and 12, said strip 14 may be used as support for supporting trousers or the like.

The new hanger is made of sheet material, such as laminated paper, cardboard, plastic ma-

terial etc., single layers of said material being not rigid enough to build a solid garment hanger therefrom. This is particularly true for the hook of the hanger, and the known hangers made entirely of cardboard or the like material have the disadvantage that the hook and the adjoining portions of the hanger frame wear out after they have been in use for a very short period. In the new improved hanger, this disadvantage of the known cardboard sheet hangers has been overcome by reinforcing said hook and the adjoining portions of the sides of the hanger frame in a manner which will now be described in connection with Figs. 2 to 4 of the drawings.

A blank as shown in Fig. 2 is cut out of a sheet of cardboard or other suitable material. The reinforcements are obtained by the utilization of folds in the portions to be strengthened involving several layers of material. The hanger according to Figures 1 and 2 has five superimposed layers 15, 16, 17, 18 and 19 for the hook, which are formed by folding as follows: First, hook layer 15 is folded about a fold line at 20, until it covers hook layer 16. Second, the hook layers 15 and 16 together are folded about two fold lines at 21, until they superimpose on hook layer 17. Third, hook layer 18 is folded about a fold line at 22, until it covers hook layer 19. Fourth, the combined hook layers 18 and 19 are folded about two fold lines at 23, until they cover the already combined layers 15, 16, 17 as shown in Fig. 4. At fold lines 21 and 23, respectively, enough fold area is provided for the different numbers of layers. Finally, a center flap 24 is turned about two fold lines at 25, until it covers the combined hook layers 15, 16, 17, 18 and 19, and two flaps 26 and 27 are folded about double fold lines at 28 and 29, respectively, until said flaps 26 and 27 superimpose on portions of the sides 11 and 12, respectively, thus reinforcing said sides 11 and 12 at the points of great stress. Also between the multiple fold lines at 25, 28, and 29 for the flaps 24, 26, and 27, respectively, enough fold area is provided to accommodate the different numbers of sheet layers covered by said flaps.

In addition to this, further reinforcements of said section of the hanger frame are obtained by the provision of extended end portions or tails 30, 31, 32 and 33 at the lower extremities of the hook layers 15, 16, 18 and 19, respectively, said extended end portions or tails covering portions of the sides 11, 12, respectively, after being folded thereon. The location of said superimposed layers along the line 3—3 of Fig. 1 is illustrated more clearly in the cross sectional view of Figure 3, which shows that the end portion or tail 33 forms the center layer of the three superimposed layers at the section line. In order to have larger supporting surfaces at the contacting points with the garments, narrow flaps 34, 35, 36 and 37 may be provided at the outer edges of the sides 11 and 12 and the flaps 26 and 27, respectively, said narrow flaps 34, 35, 36 and 37 being bent outwardly, as shown in Fig. 3. A similar narrow flap 38 may be provided at the upper edge of the straight strip 14, said flap being bent to the right side in Fig. 3, in order to obtain a larger contacting surface for the trouser or other garment to be supported by said straight strip 14.

The superimposed layers forming the hook may be of different width at least at the lower part of the hook, thus providing a sloping or step-like contacting surface at the edges for the up-

per part of the garment to be supported, as shown in Fig. 1.

The superimposed layers may be united either by gluing or by stapling or in any other manner. 5 The gluing may be carried out with or without application of pressure and/or of heat. The latter method is required, if as sheet material for the hanger thermoplastic material is used. In the example of Figs. 1, 3 and 4, wire staples 39, 10 40, 41 and 42 are provided for holding the respective layers together, said staples being driven through the superimposed layers in a conventional manner. It is also possible to use such wire staples in addition to gluing.

A modification of the hanger of Figures 1 to 4, inclusive, is shown in Figs. 5 to 8 inclusive. As the development in Fig. 5 indicates, this hanger is made of a blank having the double size of the blank of the hanger in Figures 1 and 2. The hanger frame of Fig. 5 consists of two halves 43 and 43', each being almost similar to the hanger blank in Fig. 2. Said halves are integral and are to be folded about a fold line 44 corresponding to the lowest edge of the finished hanger. Before the halves are folded about said fold line 44, each half is separately prepared by folding in the manner described above in connection with Figs. 1 to 4, inclusive. The structure and arrangement of the narrow flaps 45, 46, 47 and 48 forming the supporting surfaces for the garments are slightly different from those in Figs. 1 and 2. In Fig. 5 the narrow flaps 45 and 46 are a little wider than the narrow flaps 47 and 48. The narrow flaps 45, 46, 47 and 48 of the one half 43 of the hanger 30 are bent to one side while the corresponding flaps of the other half 43' of the hanger are bent to the opposite side, as shown in the cross sectional illustration of Fig. 8. The narrow flaps 45 and 46 lie upon the narrow flaps 47 and 48, respectively, thus stronger supporting surfaces are obtained.

The two halves 43 and 43' can be folded together in two different directions, as illustrated in Figs. 6 and 7. In Fig. 6, the center flap 24 is shown, whereas in Fig. 7 said center flap is covered, since it is one of the centrally located superimposed layers. As in Fig. 1, the superimposed hook layers of Figs. 6 and 7 have different widths, thus forming sloping or step-like contacting surfaces at the edges for the upper part of the garment to be supported. In addition to sloping the hook to one side, as shown in Figs. 6 and 7, it is possible to slope both sides symmetrically. Not only may parts of the hook be so sloped, but substantially all of the hook and corners may be so sloped.

The superimposed layers of the modification of Figs. 5 to 8 can be combined either by glueing or stapling, as already described, or in any other manner. Instead of glueing or stapling or in addition to this, small tapered flaps may be provided in the one layer which can be pressed into square apertures located at corresponding points in the adjacent layer, as illustrated in Figs. 5 to 7. After the hook layers 15 and 16 have been folded the one on the other, tapered flap 49 of hook layer 16 is pressed into aperture 50 in hook layer 15. The two combined hook layers 15 and 16 are now folded over hook layer 17 the tapered flap 51 of which is pressed into the aperture 50 of hook layer 15. A tapered flap 52 of the side 11 is pressed into another aperture 53 in hook layer 16. Then hook layer 18 is folded over hook layer 19 and tapered flap 54 of hook layer 18 is pressed into aperture 55 in hook layer 19. The

combined hook layers 18 and 19 are folded over the combined hook layers 15, 16 and 17 and tapered flap 56 in side 12 is pressed into another aperture 57 in hook layer 19. Now the center flap 24 and the reinforcement flaps 26 and 27 are folded upwardly and tapered flap 58 of said center flap 24 is pressed into aperture 55 in hook layer 19. Tapered flaps 59 and 60 of the flaps 26 and 27, respectively, are pressed into apertures 53 and 57 in the hook layers 16 and 19, respectively. The two hanger halves 43 and 43', thus prepared, can be combined, after being folded about the fold line 44, either by gluing, stapling or by means described for the single half with reference to Fig. 5, or by any other suitable means, or by a combination of the above means. The flaps and apertures for connecting the individual layers to each other may have any suitable size or shape, but the size or shape shown in the preferred modification is desirable. If necessary more or less of said flaps and corresponding apertures may be provided. A thin strip 61 of solid material, for example hard cardboard or wood, may be inserted into the fold between the connecting strips 14 and 14' of the two hanger halves 43 and 43', in order to stiffen the entire structure. Said strip 61 may be connected to the two halves 43 and 43' by gluing or stapling or in any other suitable manner.

Fig. 9 shows a modification of the hanger of Figs. 5 to 8. The hanger of Fig. 9 is also obtained from a blank having two halves folded about a fold line 44 corresponding to the lower edge of the hanger. Whereas the upper half 62 of said two hanger halves is constructed as the hanger frame in Figs. 1 to 4, the lower half 63 has no hook elements, i. e. the center part of the lower half is omitted, thus only short legs 64 and 65 remain. Said short legs 64 and 65 have laterally extended portions 66 and 67 which are to be folded on the legs 64 and 65, respectively, about fold lines 68 and 69, respectively. Thus, the lower portion of the hanger frame is stiffened by superimposing strip 14 with strip 14'. The legs 64 and 65, which are themselves stiffened by the folded portions 66 and 67, respectively, serve to reinforce the lower extremities of sides 11 and 12, respectively. A stiffening strip 61 as shown

in Fig. 5 may also be provided in the hanger of Fig. 9.

Instead of five or ten superimposed hook layers, as shown and described in the examples, any other number of such superimposed layers may be provided. The selection of the sheet material with respect to quality and thickness depends at least in part on the number of superimposed layers for the hook and frame of the hanger. For example, the hanger of Figs. 1 to 4 requires thicker and/or stronger sheet material, than the hanger of Figs. 5 to 8, which is built up with twice as much of superimposed layers than the former.

The new construction makes it possible to use inexpensive sheet material and to utilize substantially all of the sheet from which the blanks are cut without waste, so that substantially all of the sheet material serves in a functional manner within the hanger structure.

It will be obvious to those skilled in the art that various changes may be made in this hanger without departing from the spirit of the invention and therefore the invention is not limited to what is shown in the drawings and described in the specification but only as indicated in the appended claim.

What is claimed is:

A garment hanger formed from a sheet of foldable material and comprising a body portion of approximately isosceles triangular shape, a hook-like suspension means projecting from the apex of the body portion opposite the base, a reinforcing member integrally connected with each side edge of said hook-like suspension means, said reinforcing members each having a hook-like portion and an integral lateral elongated extension thereof, said reinforcing members being foldable at their juncture with said suspension means along lines perpendicular to the base of the hanger body to thereby position said hook-like portions overlying said hook-like suspension means and said extensions overlying the adjacent sides of the hanger body, and means for securing said reinforcing members in their folded positions to the body portion of the hanger.

MICHAEL GLASER.
